(57) **CLAIM**

The ornamental design for the eyelash and eyebrow protector, as shown and described.

DESCRIPTION

FIG. 1 is a perspective view of an eyelash and eyebrow protector.

FIG. 2 is a frontal view of an eyelash and eyebrow protector.

FIG. 3 is a rear view of an eyelash and eyebrow protector.

FIG. 4 is a profile view of an eyelash and eyebrow protector.

FIG. 5 is an alternate view of the eyelash and eyebrow protector.

FIG. 6 is an aerial view of an eyelash and eyebrow protector.

FIG. 7 is bottom view of an eyelash and eyebrow protector; and,

FIG. 8 is a perspective view of an individual wearing an eyelash and eyebrow protector.

The broken lines in FIGS. 1, 2, 3, 6, 7 and 8 are shown for the purpose of illustrating portions of the eyelash and eyebrow protector and form no part of the claimed design. The dash-dot lines displayed in FIG. 8 surrounding the eyelash and eyebrow protector show environment in which the design is associated.

1 Claim, 6 Drawing Sheets
